ELECTRICAL SWITCH ENCLOSURE

Robert E. Larkin, Lisbon, Wis., assignor to Cutler-Hammer, Inc., Milwaukee, Wis., a corporation of Delaware

Filed July 25, 1960, Ser. No. 61,498

Term of patent 14 years

(Cl. D26—13)

Fig. 1 is an isometric view of an electrical switch enclosure, showing my new design;

Fig. 2 is a front elevational view, the rear being substantially a mirror image thereof;

Fig. 3 is a side elevational view, the opposite side being substantially a mirror image thereof; and

Fig. 4 is a top plan view thereof.

I claim:

The ornamental design for an electrical switch enclosure, substantially as shown and described.
